UNITED STATES PATENT OFFICE.

JAMES HARRISON CAMPER, OF HUNTINGTON, WEST VIRGINIA.

HOUSEHOLD ARTICLE.

Application filed April 28, 1923. Serial No. 635,292.

This invention relates to improvements in household articles and has for an object the provision of a novel form and arrangement of a clothes rack.

5 An object of the invention is the provision of a clothes rack which may be readily folded or collapsed so as to occupy a minimum amount of space, but which will provide considerable hanging space when 10 arranged for use.

With the above and other objects in view, the invention further includes the following novel features and details of construction, to be hereinafter more fully described, illustrated in the accompanying drawings and pointed out in the appended claim.

In the drawings:—

Figure 1 is an elevation of the clothes rack in set up position.

20 Figure 2 is an end view of the same.

Figure 3 is a view similar to Figure 1 showing the clothes rack partly collapsed.

Figure 4 is an enlarged sectional view on the line 4—4 of Figure 2.

25 Referring in detail to the drawings, similar numerals refer to similar parts throughout the several views.

The invention constitutes a clothes rack which comprises a top section 38, a bottom 30 section 39 and an intermediate section 40, each of which includes spaced standards 41, 42 and 43 respectively. The standards 41 have their upper ends connected by bars 44 and to provide for this the ends of these 35 bars have rigidly secured thereto corner plates 45. These plates include spaced ears 46 between which the upper ends of the standards 41 are pivotally secured in a manner to permit them to fold inwardly.

40 The standards 41 and 43 are connected by a hinge joint 47, which joint also includes spaced ears for receiving the adjacent ends of the standards 41 and 43, while the hinge is offset. The hinge is cut away to provide 45 an opening 48 through which passes the ends of a brace bar 49, there being one of these bars at each side of the rack. The bars 49 carry at their outer ends oppositely disposed arms 50 which act as stops to limit

50 the outward movement of the standards 41 and 43. An offset centering block 51 is provided for each of the bars 49.

The standards 42 and 43 are connected by substantially T-shaped brackets 52 to which 55 are connected the opposite ends of spaced bars 53. The brackets 52 include opposite-

ly disposed spaced ears 54 and the adjacent ends of the standards 42 and 43 are pivotally secured between these ears as shown at 55 so as to permit these standards to be 60 folded inwardly upon the opposite edges of the bars 53. The standards are connected by bars or rungs 56 which provide hanger bars.

When set up for use, the rack provides 65 spaced substantially rectangular frames which include vertical standards, top and bottom connecting bars and intermediate brace bars. In addition, the bottom bars 53 are connected to the standards 42 by means 70 of oppositely inclined braces 57. These braces are of sectional formation and the sections are hingedly connected as at 58, their hinged movement being limited in one direction by means of stops 59. 75

By moving the adjacent ends of the standards 41 and 43 relatively inward as shown in Figure 3 of the drawings, the said standards may be folded along the opposite edges of the brace bar 49 with the bar 80 44 superimposed upon the standards 41. When in this position, the arms 50 of the brace bars 49 will overlap the brackets 45 and 52. By breaking the joints of the inclined brace 57, the standards 42 may be 85 folded inwardly beneath the bars 53 so that the rack will then be compactly arranged for insertion within the frame 13 of the table.

It will be apparent from the foregoing 90 description and accompanying drawings, that the invention provides an exceedingly useful household article which being sufficient in drying an ordinary family wash when so set up and being so constructed as 95 to permit the sections so forming the rack as to be folded one upon the other whereby the entire rack may be compactly stored in a confined area.

The invention is susceptible of various 100 changes in its form, proportions and minor details of construction and the right is herein reserved to make such changes as properly fall within the scope of the appended claim. 105

Having described the invention what is claimed is:—

A collapsible clothes rack comprising a pair of spaced parallel frames each frame 110 comprising a top section, a bottom section and an intermediate section, means hingedly connecting said sections, the hinged con-

nections of the top and intermediate sections being each formed with an opening, a brace for each frame extending freely through said openings and being provided at its ends with oppositely disposed arms, said top and intermediate sections being movable inwardly relatively to said brace

and being limited in outward movement by said arms, oppositely inclined collapsible braces each pivotally connected at opposite ends to the intermediate and lower sections and rungs extending between said frames. 10

In testimony whereof I affix my signature.

JAMES HARRISON CAMPER.
